TRAFFIC CONTROL SYSTEM

Copeland C. MacAllister, Winchester, Mass., assignor to General Electric Company, a corporation of New York

Application August 6, 1942, Serial No. 453,813

1 Claim. (Cl. 177—337)

My invention relates to traffic signal systems and more particularly to systems wherein a group of intersection controllers are each brought into and maintained in synchronous operation with a master controller.

One object of my invention is to provide improved apparatus for controlling the intersection controllers during periods of resynchronization.

For a better understanding of my invention, together with other and further objects thereof, reference is had to the following description taken in connection with the accompanying drawing, and its scope will be pointed out in the appended claim.

The accompanying drawing illustrates diagrammatically a traffic control system embodying my invention.

Referring to the drawing in detail, a master controller 10, illustrated merely by a rectangle of dotted lines, includes a switch 11 operated by a cam 12 and controls a group of intersection controllers through a circuit including any one of a group of conductors 13, 14 and 15 selected by a selector switch 16.

Only one of the intersection controllers controlled through this group of conductors is illustrated diagrammatically. It is preferably of the type fully described in United States Letters Patent 2,236,299, issued to Reid, March 25, 1941. This controller operates groups of traffic signals 17 and 17' connected by a cable 18 to a switching mechanism 19 indicated merely by a rectangle. This switching mechanism may be of any suitable type operable step by step in response to current impulses to energize a predetermined combination of signal lamps at each step. Each combination of signals is held for a predetermined time period which constitutes a signal period.

The timing mechanism, also a part of the controller, for determining the length of the time period between the step-by-step actuations of the switch mechanism 19 is driven by a motor 20 provided with an operating field 21, a braking field 22, a driving shaft 23 and a driving pinion 24. The pinion 24 is in driving engagement with a gear 25 mounted upon a dial shaft 26 to which is attached a dial 27. The dial, which may be termed a timing dial, is provided with two concentric rows of radial slots 28 and 29. The outer row of slots 28 carries a group of keys 30 to 35, inclusive, and the inner row of slots 29 carries a group of keys 37 to 39, inclusive. The keys are spaced from each other by being positioned in selected slots,

of which 100 are available in each row, to actuate switch contacts placed in the path of movement of these keys. In the illustrated controller, five resilient switch arms 40 to 44, inclusive, are mounted parallel to each other upon a single suitable block 45 and the arms are provided with actuating blocks attached to the forward ends of the switch arms. Contact arm 40, nearest to the dial, is provided with an actuating block 46 the end of which extends into the path of movement of and is raised by each of the keys 31, 32, 33, 34 and 35 as they are moved past the block. At each instance a contact 47 carried by the contact arm is raised into engagement with a stationary contact 48, thereby momentarily completing a circuit through a conductor 49 to the switching mechanism 19. The contact arm is connected by a conductor 50 to the switching mechanism 19 and the completion of this circuit sends a current impulse through the circuit which effects an actuation of the switching mechanism to change to a succeeding combination and period of the signals 17 and 17'.

25 The second contact arm 41 is provided with an actuating block 51 and is operated by the key 30 only, this key being provided with a notch to avoid actuating block 46. This actuation occurs once during each revolution of the dial 27, thereby closing a circuit at contact 52 on the arm 41, and a stationary contact 53. The stationary contact 53 is connected to the switching mechanism 19 by a conductor 54 and the contact arm 41 is connected to the switching mechanism by a conductor 54'. In a single rotation of the dial 27, which is a complete cycle of operation for the dial, the contacts 47, 48 are operated to effect at each actuation an operation of the switching mechanism 19, and the contacts 52, 53 are operated by the key 30 to complete a cycle of operations. The key 30 and the circuit closed thereby are provided for operating the switching mechanism at one selected position of the dial. The switching mechanism is arranged so it will move up to a corresponding position in its cycle of operation and will move past that position only when key 30 actuates its contacts, thereby to maintain a predetermined relationship between the cycle of operation of the dial and the similar cycle of operation of the switching mechanism. The switching mechanism 19 may be any suitable program switching mechanism but is preferably of the rotating drum type actuated by a

magnet and ratchet device, as illustrated and described in the above mentioned Reid patent.

For the purpose of maintaining a predetermined relationship between the operating cycle of this intersection controller and the operating cycles of other similar controllers controlled by the same master controller, each secondary controller is provided with one or more circuits and with the necessary switches to energize the braking field 22 of the dial motor 20 whenever the controller is out of its proper operating relationship. In the illustrated example three contact arms 42, 43, 44 are provided in each secondary controller, each being provided with a suitable actuating block, which are operated respectively by the dial keys 37, 38 and 39, the key 37 operating the arm 42, the key 38 operating the arm 43 and the key 39 operating the arm 44. The contact arms are respectively connected to the common conductors 13, 14 and 15 through conductors 20 55, 56 and 57, other controllers being connected to the same common conductors by conductors 55', 56', 57' and 55'', 56'', 57''. The three conductors and three contact mechanisms are provided so as to make it possible to operate the secondary controller in the three distinct relationships with the master controller which are determined by the positioning of the respective keys in the inner row of slots 29. Only one of the conductors 13, 14 and 15 is effective at any one time 30 to carry current to the field 22, being selected by the selector switch 16. If switch 16 is set as illustrated in the drawing, a circuit is established to the common conductor 15, conductor 57, through contact arm 44, through its respectively 35 operated contacts to a conductor 58 and through field 22 to ground whenever the key 39 moves under and raises the actuating block of the contact arm 44. The circuit to the selector switch 16 and to the common conductor passes through the master controller and is arranged to be broken by the master controller switch 11 once during each operating cycle. When the current in the field 22 is so interrupted, the dial in each stopped 40 secondary controller moves its key to break the circuit at the respective contacts and thereby is free to operate for a complete revolution of the dial before the key again closes the braking, or resynchronizing, contacts to stop the dial.

In accordance with my invention the master switch 11 is not connected directly to the selector switch 16 but is connected through an intermediate auxiliary timing apparatus which may be assembled in the casing of the master controller or may be assembled in a separate casing indicated generally by the dotted rectangle 59. This apparatus includes a timing dial 60, similar to the timing dial 21, driven by a motor 61 provided with a driving field 62 and a braking field 63. The timing dial is provided with one or more groups of keys such as 64, 65 and 66, also 67, 68 and 69. The keys operate contact arms 70, 71 and 72, respectively. The contact arm 70 is provided with a pair of normally open contacts 73, 74, the contact arm 71 is provided with a pair of normally open contacts 75, 76, and the contact arm 72 is provided with a pair of normally closed contacts 77, 78.

This auxiliary timer also includes a relay, comprising an operating coil 81 arranged to actuate a normally closed contact 88, and a switch comprising an operating coil 93 arranged to actuate contacts 87, 91 and 95 of which 87 and 91 are normally open and 95 is normally closed. The circuits controlled by the energization and de-

energization of these coils through their respective contacts will be traced in the description of the operation of the system.

The master switch 11 normally establishes a circuit from a source of current indicated by a plus sign through a conductor 80, relay coil 81, conductor 82, conductor 83, through the normally closed contacts 77, 78, contact arm 72 and conductor 84 to the selector switch 16. The circuit thus traced places potential upon the common conductor 15 and whenever the contact arm 44 of a secondary controller is actuated current flows to the braking field 22 to stop immediately the motor and the timing dial, thereby retaining the contact arm in the contact closing position. This position is retained by the secondary controller dial until the braking field circuit is opened. This period is normally referred to as the resynchronizing period and if the master switch alone were to control the circuit this period could be of a length almost equal to the length of a signaling cycle. If traffic were correspondingly held up on a busy highway, considerable congestion would ensue. It is therefore desirable to limit the available synchronizing time in any one signal cycle to a short period and to distribute the total required resynchronizing time period in increments of this total time period in successive cycles of operation. It is therefore the function of the auxiliary timing device, operating through the dial 60, to arrange for the release of the secondary controllers within a predetermined short time period after the first secondary controller of the system has been stopped.

The dial 60, as shown in the drawing, is in a position at which the key 65 closes the contacts 75 and 76. This establishes a circuit to the braking field 63 thereby effecting its stoppage at this position. The circuit may be traced from the grounded end of the braking field 63 through the field, through a conductor 85, through the contacts 75, 76, contact arm 71, conductor 86, closed switch contact 87 to a source of current indicated by a plus sign. In the position illustrated, therefore, the dial 60 is stationary.

During operation, if a secondary controller falls out of synchronism and current flows through the master controller switch 11 and the auxiliary timing device to the conductor 15 through the circuit as traced, the auxiliary timer relay coil 81 is energized and opens its contacts 88 to break a circuit from the source of current indicated by the plus sign at the relay contacts 88, through conductor 89, conductor 90, closed switch contact 91, conductor 92 to the switch coil 93 and through the coil to ground, thereby deenergizing the switch coil 93 and effecting the opening of the contacts 87 and 91 and the closing of contacts 95 controlled by this coil. The closing of contacts 95 establishes a shunt circuit around the coil 81. This circuit may be traced from conductor 80 through conductor 96, contact 95 to conductor 82. This is a low resistance path and deenergizes coil 81 sufficiently to cause it to drop and thereby reclose the contact 88.

The opening of contact 87 by the deenergization of the coil 93 breaks the circuit to the braking field 63 and allows the motor 61 to drive the auxiliary timer dial 60 to move the key 65 and thereby break the braking coil circuit at the contacts 75, 76. Within a predetermined period determined by the speed of the dial 60 and by the positioning of the subsequent key 69 in the dial, the key 69 is moved into position to lift the contact arm 72 to separate the contacts 77, 78 and

thereby break the circuit to the conductor 15. The effect of this momentary breaking of the circuit is the same as the breaking of that same circuit by the master controller at switch 11 and permits all of the secondary controllers which have been stopped by the energization of the conductor 15 to resume operation. The dial 60 continues to move and within a short time its key 67 is moved into position to operate momentarily the contact arm 70 to close a circuit at contacts 73 and 74. The circuit established thereby may be traced from the source of current at relay contact 88 (this relay having closed at the instant at which the contact 95 was closed by operation of the coil 93), through conductor 89, conductor 90, contacts 73, 74, contact arm 70, conductors 94, 92 to relay coil 93 and to ground, thereby effecting a reclosing of the switch contacts 91 and 87 and an opening of the contact 95.

The closing of switch contact 91 establishes a holding circuit for the coil 93 through conductor 89 and relay contacts 88. The closing of this contact 91 maintains the energization of coil 93 though the dial moves the key 67 past the actuating block for contact arm 70 and causes the contacts 74, 73 to separate. The closing of contact 87 by the energization of coil 93 establishes a circuit from a source of current through the contact 87 and the conductor 86 to contact arm 71. The opening of contact 95 opens the shunt circuit around the relay coil 81.

The dial 60, with this arrangement of the switch and relay contacts within the auxiliary timer, continues to operate and moves key 68 into position to close the braking coil circuit for its driving motor 61 at the contacts 75, 76 as previously traced, the closing of contact 87 having placed potential on contact arm 71 through conductor 86. The dial 60 then remains stationary until the next energization of the relay coil 81 by current flowing to one of the braking fields of the secondary controllers.

The dial 60, together with its driving apparatus, relay 81 and the switch 93, may be enclosed within a single controller casing as indicated by dotted lines or may be built into the master controller 11. Its function, as above pointed out, is to deenergize the common or interconnecting conductor between the master controller and the secondary controllers at a predetermined period of time after the beginning of flow of current within that conductor. It is obvious that as soon as a single controller calls for braking current the

timing apparatus begins to operate and interrupts that current within a predetermined time period after the inception of current flow. Any subsequently stopped secondary controller that 10 may be connected to the common conductors, as indicated at 57', 56', 55' and 57'', 56'', 55'', is restarted at the end of that predetermined period of time after the first controller is stopped, so that each of the secondary controllers is not necessarily stopped for the full period for which the auxiliary timing apparatus is set. The auxiliary timing apparatus merely provides for a limitation of the maximum time for which any secondary controller may be stopped during any one cycle. As a result of this operation, the secondary controllers continue operation in out-of-synchronism relationship through successive cycles but with a successively diminished out-of-synchronism relationship. Such out-of-synchronism relationship may exist when the intersection controllers are first placed into operation and occurs whenever the selector switch 16 is operated to select a different common conductor through which a corresponding and predetermined operating relationship is selected.

What I claim as new and desire to secure by Letters Patent of the United States is:

In a traffic signal system, a combination of a master controller operated at a predetermined 30 signal cycle, a group of secondary controllers each including a timing mechanism and operating at a signal cycle length corresponding to the signal cycle length of said master controller, current operated means in each controller for stopping 35 said controller at a predetermined instant in its operating cycle, a common circuit connecting said secondary controllers to said master controller, means for interrupting said common circuit for restarting said secondary controllers at a predetermined instant in the master controller operating 40 cycle, an auxiliary timer, means for starting said auxiliary timer at the instant current flows to any one of said secondary controllers in said common circuit, means operated by said 45 auxiliary timer for interrupting said common circuit within a predetermined time period, and means for effecting operation of said auxiliary timer for a full preset operating period independently of current variations resulting from the 50 variations in the number of controllers being stopped for resynchronization in said common circuit during the operating period.

COPELAND C. MACALLISTER.
